(57) **CLAIM**

The ornamental design for an articulated tool-holding arm, as shown and described.

DESCRIPTION

FIG. 1 is a right side view with arm extended of the articulated tool-holding arm showing my new design;

FIG. 2 is a top view with arm extended of the articulated tool-holding arm;

FIG. 3 is a bottom view with arm extended of the articulated tool-holding arm;

FIG. 4 is a perspective top, right view with arm extended of the articulated tool-holding arm;

FIG. 5 is a left side view with arm folded of the articulated tool-holding arm;

FIG. 6 is a right side view with arm partially folded up of the articulated tool-holding arm;

FIG. 7 is a right side view with arm partially folded down of the articulated tool-holding arm;

FIG. 8 is a right side perspective view with the arm extended of the articulated tool-holding arm; and,

FIG. 9 is front view with arm extended of the articulated tool-holding arm.

The dashed line showing of the label in FIGS. 1, 4, 6, 7 and 8 form no part of the claimed design.

The broken lines in the drawings depict unclaimed environmental subject matter.
